UNITED STATES PATENT OFFICE.

JESSE A. LOSEE, OF TITUSVILLE, PENNSYLVANIA.

RADIATOR.

SPECIFICATION forming part of Letters Patent No. 443,531, dated December 30, 1890.

Application filed March 29, 1890. Serial No. 345,843. (No model.)

To all whom it may concern:

Be it known that I, JESSE A. LOSEE, of the city of Titusville, in the county of Crawford and State of Pennsylvania, have invented certain new and useful Improvements in Radiators; and I do hereby declare the following to be a full, clear, and exact description of the invention, such as will enable others skilled in the art to which it appertains to make and use the same.

My invention relates to an improvement in radiators, its object being to so construct a radiator that a large surface thereof will be exposed and that the circulation of air over such surface shall not be retarded, but, on the contrary, shall be assisted.

A further object is to provide a radiator adapted to be heated by means of steam, hot water, or otherwise, said radiator being constructed and arranged in such manner that air circulating over its surface shall be permitted to expand as its temperature increases without in any manner retarding the free circulation of the air.

With these objects in view the invention consists in a radiator each section of which is made wider at its top than at its bottom and thicker at its bottom at its top.

It further consists in a radiator having ribs or projections which diverge from bottom to top thereof; and the invention further consists in certain novel features of construction and combinations and arrangements of parts, as hereinafter set forth, and pointed out in the claim.

In the accompanying drawings, Figure 1 is an elevation of one section of my improved radiator. Fig. 2 is an edge view of several sections. Fig. 3 is a bottom view of four sections. Fig. 4 is an elevation of one section adapted to receive hot water. Fig. 5 illustrates plan views of the forms shown in Figs. 1 and 4. Figs. 6, 7, 8, and 9 are views of modifications.

The radiator adapted to be heated by steam is built of any desired number of thin hollow sections A, connected at the bottoms by means of the usual right-hand nipples B, and held together at their tops by means of a bolt C, said bolt passing through all the sections and provided at one end with a head and at the other end with a nut; or, if desired, said bolt

or rod C may be screw-threaded at both ends for the reception of suitable nuts.

Each section of the radiator is provided with a series of preferably hollow ribs or flanges a, running from the bottom to the top thereof. Now, should the ribs be arranged parallel with the vertical axis of the device or vertical, so that the spaces between them will be of the same width throughout, the air starting at the bottoms of the passages formed by these ribs will increase in temperature as it ascends and consequently expand, such expansion tending to retard the rise of air beneath it, and thus to retard the free circulation of air over the surface, or, more correctly speaking, through the channels or flues on the radiators. As the heating capacity of a radiator depends largely upon the amount of air that can be brought in contact with its heating-surfaces, if the free circulation of the air be retarded or interfered with the heating capacity of the radiator will of course be diminished. Therefore, in order to correct this serious defect in the construction of radiators I construct the sections thereof as shown in the drawings—namely, each section is made, preferably, flat and wider at its top than at its bottom and thicker at its bottom than at its top. The ribs or flanges a are arranged on the opposing faces of each section and diverge from the bottom of the section, thus producing a series of passages or channels wider at their upper than at their lower ends.

By producing channels or passages in the manner above described it will be seen that the air as it rises and increases in temperature is given space in which to expand, thus permitting a free circulation of air through the channels or passages.

When it is desired to heat the radiator by means of hot water, the long bolt or rod C will be dispensed with and the several sections fastened together at their lower ends by means of short bolts b. In this case the nipples at the lower ends of the sections are dispensed with and in their place a series of perforated bosses c are made on the several sections. The upper ends of the sections are connected together by right-handed screw-threaded nipples d. When the several sections of the radiator are in position and the nipples d in

place, washers *c*, of elastic material, are inserted between the bosses *c* and the bolts *b* tightened, thus making a close connection between the boss, one section with the boss of the next adjacent section. By this construction a hot-water radiator will be produced which will be of simple construction, easy to manufacture, and by bolting the sections together at the lower end the screen or cover 5 ordinarily placed on radiators of this class will be dispensed with, thus decreasing the expense of manufacture and still maintaining the effectiveness of the radiator.

If desired, the ribs or flanges may be 10 made on one face only of the sections of the radiator, as shown in Fig. 9. By this construction the cost of manufacture is materially lessened without in any degree impairing the effectiveness of the device.

Having fully described my invention, what 20 I claim as new, and desire to secure by Letters Patent, is—

A radiator consisting of a series of hollow sections, each section thicker at the bottom than at the top and wider at the top than at 25 the bottom, each section being provided on its opposite faces with ribs diverging from the base upwardly, substantially as set forth.

In testimony whereof I have signed this specification in the presence of two subscribing witnesses.

JESSE A. LOSEE.
